UNITED STATES PATENT OFFICE.

WILLIAM THOMPSON, OF LEEDS, ENGLAND.

APPARATUS FOR DRAWING FIBERS.

SPECIFICATION forming part of Letters Patent No. 461,855, dated October 27, 1891.

Application filed June 27, 1891. Serial No. 397,685. (No model.) Patented in England September 4, 1889, No. 13,913.

To all whom it may concern:

Be it known that I, WILLIAM THOMPSON, a subject of the Queen of Great Britain, residing at Larkfield, Rawdon Leeds, in the county 5 of York, England, have invented a certain new and useful Improvement in Apparatus for Drawing Fibers, (for which I have obtained a patent in Great Britain under date of September 4, 1889, No. 13,913,) of which 10 the following is a specification.

My invention relates to improved apparatus for the drawing of fibers, it being specially applicable for dealing with fiber of short staple; and it may be used in combination with 15 a mule or a spinning-frame, or the fibers so drawn may be twisted from the improved appliance direct.

The improved apparatus consists of a series of suitable rollers over and under which are 20 passed two endless bands, preferably of india-rubber or elastic band or web, which work one over the other, so as to confine and carry the fibers between them until arriving at the delivery end, when they are diverted by guide- 25 rollers so as to separate or open the bands for the delivery of the fibers, the bands returning to the leading-in or starting rollers. The studded rollers may be of metal or hard wood and may be provided with top or weight- 30 ing rollers.

I have obtained satisfactory results from the use of cog-wheels together with the elastic bands; but I prefer the studded rollers, as first mentioned.

35 To clearly explain my invention, reference is made to the accompanying drawings, in which—

Figure 1 is a side elevation of my apparatus. Fig. 2 is a front elevation. Fig. 3 is a cross- 40 section on the line xx of Fig. 2. Fig. 4 is an enlarged view of part of two of the rollers and bands. Fig. 5 is a section showing a modified form of roller. Fig. 6 is a detail view of a further modification.

45 The end frames 1 1 carry in drop-bearings the axles of the three studded rollers 2 3 4, which are geared together by the gears $a b c$, carried by the axles, the roller 3 being adjustable by means of the strap 5, in which 50 it rests, which strap may be moved up and down by means of the screws 6 6. The two rollers 7 and 8 are guide-rollers, over which

passes the endless band 9, said band also passing over the studded surface of the roller 3. The second band 10 passes over the studded 55 surface of the rollers 2 and 4 and over the roller 3. The gears $a b c$ are so arranged that the roller 3 is caused to travel faster than the roller 2 and the roller 4 faster than the roller 3, the elastic band 10 stretching to allow of 60 this between the rollers 2 and 4 and returning to its normal tension when passing over the guide-roller 11. In this way the requisite 65 drawing out or drafting of the fibers is attained through the variation of the surface 70 speeds of the roller-bands 9 and 10. The fiber is entered between the roller-bands at the guide-roller 7 and its exit is at the guide-roller 8. It will be obvious that the draft 75 may be varied as the surface speed of the two 80 endless bands is changed. Either single bands 9 and 10 may be employed or a number traveling over the same rollers, as shown in Fig. 2.

The studded rollers 2 3 4 may consist of 85 studs or pins 12, driven or otherwise fixed 75 around the circumference of the roller; or a roller covering of wire cards set in a felt or other thick foundation may be employed, as shown in Fig. 5; but I do not confine myself to any special form or kind of pin, so long as 80 the rollers 2 3 4 are provided with studded, spiky, or porcupine surfaces; nor do I confine or limit myself to the use of three of such rollers, though I prefer the same, as a lesser or greater number may be employed. 85

In some cases, as in Fig. 6, I employ stud or cog wheels, the pitch and foundation of the teeth being such as to permit the cogs to partly gear, though covered by the india-rubber or other elastic sheet covering, around the teeth 90 and which is by one tooth stretched and forced in and between two teeth of the other wheel, so that by the use of same I secure for particular fibers the desired short draft—that is to say, as the fiber is carried down between 95 the teeth it is elongated or drawn out, according to the depth and foundation of the teeth on the wheels employed.

What I claim is—

1. In apparatus for drawing fibers, and in 100 combination, two or more rollers, a suitable guide-roller, an endless elastic band passing around the same, an intermediate roller, guide-rollers, and an intermediate endless

elastic band passing around the same, all three rollers being driven at increasing speeds, so that the fiber introduced between the two bands is drawn out in its passage between them, substantially as described.

2. In an apparatus for drawing fibers, the endless elastic bands and the supporting-rollers therefor, said rollers having toothed surfaces and operating to stretch or draw out the bands in their passage between them.

3. In an apparatus for drawing fibers, the two elastic bands arranged to be face to face,

and the supporting-rollers therefor, the said bands being stretched at one point of their movement, substantially as described.

15

In testimony whereof I have hereunto set my hand in the presence of two subscribing witnesses.

WILLIAM THOMPSON.
